DESIGN FOR A COMBINED FIREPLACE BASKET AND GRILL

Seymour B. Kronenberg, Birmingham, Ala.

Application May 13, 1944, Serial No. 113,571

Term of patent 3½ years

(Cl. D81—18)

To all whom it may concern:

Be it known that I, Seymour B. Kronenberg, a citizen of the United States and resident of Birmingham, in the county of Jefferson and State of Alabama, have invented a new, original, and ornamental Design for a Combined Fireplace Basket and Grill, of which the following is a specification, reference being had to the accompanying drawing, forming a part thereof.

In the drawing:

Fig. 1 is a front perspective view of a combined fireplace basket and grill embodying my new design.

Fig. 2 is a rear elevational view thereof; and
Fig. 3 is an end elevational view thereof.

I claim:

The ornamental design for a combined fireplace basket and grill, substantially as shown.

SEYMOUR B. KRONENBERG.
